Attorneys.

UNITED STATES PATENT OFFICE.

MELVILLE S. WEILMAN, OF CINCINNATI, OHIO.

DRYING AND CONVEYING MACHINE.

1,411,247.

Specification of Letters Patent. Patented Mar. 28, 1922.

Application filed June 22, 1920. Serial No. 390,735.

To all whom it may concern:

Be it known that I, MELVILLE S. WEILMAN, a citizen of the United States, and resident of Cincinnati, in the county of Hamilton and State of Ohio, have invented certain new and useful Improvements in Drying and Conveying Machines, of which the following is a specification.

My present invention relates to improvements in apparatus for drying and facilitating the conveying and packing of articles and is designed more particularly for use in connection with chocolate coated candies.

The invention pertains more specifically to the type of apparatus in which trays to hold the articles to be dried are moved in an endless series from the receiving point to the packing point or table, the material being dried in transit.

The invention aims to provide apparatus of extreme simplicity which secures a maximum period of drying while occupying a minimum amount of floor space, and the invention includes the novel features of construction and arrangement and combination of parts hereinafter described and particularly defined by the appended claims.

An embodiment of my invention is illustrated in the accompanying drawings, in which:

Figure 1 is a side elevation with certain frame parts shown by dot and dash lines for convenience of illustration;

Fig. 2 is a partial plan view, and

Fig. 3 is a side elevation of a modification. Referring by reference characters to these drawings, the numerals 1, 1^a, and 2, 2^a designate standards or frame members designed to support the working parts hereinafter described, the standards 1 and 1^a on the near side, Fig. 1, being shown by full lines and those on the opposite side being shown by dot and dash lines to clearly distinguish them. The standards are provided at their lower ends with feet adapted to be bolted or screwed to the floor as shown, and are connected to and support, at their upper ends, a table 3, which braces the standards and which serves for the storage of boxes to be used by the operators or attendants for packing the articles.

The trays upon which the articles are to be placed are indicated at 4 and are carried by two sets of staggered or offset endless chains 5 and 6 which pass around driving and guide wheels or sprockets in a zigzag

fashion or in a back and forth direction in different successive planes.

The driving wheel for the chain 5 is indicated at 5^a and the guide wheels or sheaves 60 at 5^b while the driving and guide wheels for the chain 6 are similarly designated 6^a and 6^b. The driving wheels referred to are carried upon shafts designated 7 and 8 respectively and it will be observed that the 65 shaft 8 is set nearer the front end of the machine (the left end Fig. 1) than the shaft 7, or staggered or offset in relation thereto.

The guide wheels or sheaves may be journaled on stub axles designated 7^a and 8^a respectively and these stub axles are displaced or staggered relatively to each other in the same manner as the shafts 7 and 8.

The trays, which may conveniently be formed from sheet metal, wood or other 75 materials, are mounted upon and secured to frames, or supports, which include a diagonal bar or rod 9 and side members 9^a, as clearly shown in Fig. 2, where one tray has been omitted to show the supporting frame 80 in full lines.

It will thus be seen that the bar 9 extends substantially diagonally of the trays from the rear corner on one side to the front corner on the opposite side. At these 85 corners the rods or bars 9 are provided with chain engaging extensions, the extensions 9^b engaging the chains 5 and the extensions 9^c engaging the chains 6, the engagement being effected by any suitable 90 pivotal connection between the extensions and the corresponding chain links. It will thus be seen that each tray is supported from two of its diagonally opposite corners only, and as the chains pass around the driving 95 and guide pulleys the trays will travel with the chains and be maintained thereby in a horizontal position.

The topmost driving and guide sprockets or wheels are located at a height convenient 100 for the operator in loading and unloading. The loading station is indicated at A and the direction of travel of the chains and trays by the arrow, Fig. 1. The upper left hand tray as shown in this view is in convenient position for the operator to place the articles, for example, chocolate coated candy, which is on an enameled paper sheet, on the tray, which is then carried down into the next lower position or line of travel 110 while still kept horizontal, whence it is conveyed toward the rear of the apparatus.

Here the chains travel around the rear guide sheaves which lower each successive tray another step, and so the trays travel back and forth at successively lower levels until 5 the lowest level is reached. The trays then travel to the extreme rear end of the apparatus where the guide rollers are so disposed that the chains elevate them to the taking off position or packing station. Here the 10 operators remove the articles and pack them in boxes which have been accessibly stored on the shelf 3, before referred to. It will be understood that the chains move very slowly so that ample time is allowed for the 15 articles to dry during the back and forth movement referred to and before the packing station is reached, and sufficient time elapses while the trays are moving on the upper level from the rear to the front to 20 enable all the articles to be removed and boxed.

Any suitable means may be provided for driving the chains and I have shown as a 25 convenient means an electric motor 10 which, through a suitable belt 11 and pulleys or wheels, drives a shaft 12. This shaft 12 carries two other pulleys 13 and 14 which are connected by belts with pulleys 15 and 16 fastened on shafts 7 and 8 respectively. 30 I prefer to provide, above the shelf 3, an endless conveyor belt 17 driven from the same motor, upon which the operators may place the filled boxes to be conveyed to any convenient place. 35 It will be understood that any convenient means may be provided to prevent the sagging of the horizontal portions of the chains between the rollers or the sagging of the trays, such as frame bars 18. 40 Shelves may be provided for convenience of the operators as indicated at 19, provided with cutaway portions 19^a, in which the operators may stand. In using the apparatus, the taking off space may be utilized 45 to facilitate packing boxes with mixed chocolates if desired. For example boxes would be supplied to the trays at the left hand end of the apparatus (Fig. 1) and as the boxes

were moved successively past the attendants 50 stationed at positions 19^a, they could place the various kinds of candy in the boxes from supplies on shelves 19.

A receptacle for chocolate scrapings may also be provided as indicated at 20.

In Fig. 3 I have shown an arrangement 55 designed to economize floor space when this is necessary, and to this end I so dispose the guide rollers that the trays are moved vertically in a zigzag or to and fro manner. In this view A' designates the feed end of the 60 apparatus and B the position when the trays are unloaded.

Means may be provided to prevent any liability of tilting of the trays at the loading station which might occur should an operator inadvertently bear too heavily on one corner of a tray. 65

Such means may conveniently take the form of bars 21 carried by the uprights 1 and 2 and overlying the upper end edges 70 of the trays which would prevent either one of said edges rising under such tilting action, but would not interfere with the bodily downward movement of the trays as the chains pass around the rollers. 75

What I claim is:

1. An apparatus of the character described including a plurality of trays, endless flexible elements adapted to travel in a circuitous path, means at diagonally opposite points only of the trays for attaching said trays to the flexible elements and upon which the trays are entirely supported throughout its path of travel. 80

2. An apparatus of the character described including a plurality of trays adapted to travel in a circuitous path part of which path includes a horizontal portion, and means to positively prevent tipping of said trays when they travel in said horizontal portion of said path. 90

3. The device of claim 2 said means including a member projecting over said trays.

In testimony whereof, I affix my signature,

MELVILLE S. WEILMAN.
